ADJUSTABLE BLADING FOR FLUID FLOW MACHINES

Warren William Houghton, Manchester, Mass., assignor to General Electric Company, a corporation of New York

Filed Nov. 25, 1955, Ser. No. 548,992

5 Claims. (Cl. 253—55)

This invention relates to adjustable blading for use in fluid flow machines generally and particularly for use in compressors, and turbines where it is necessary to effect optimum efficiency over a wide range of operating conditions. It has for some time been appreciated by turbine compressor designers that where a flexible fluid flow machine is desired which will operate over a large range of operating conditions, it is highly desirable that the effective flow area of the nozzle diaphragm in the case of a turbine, or diffuser assembly in the case of a compressor, be adjustable in order to minimize losses. A conventional manner for providing the desired adjustable effective flow area feature has been to provide a nozzle ring or diffuser assembly in which the nozzle or diffuser vanes are pivotally mounted for rotation through a limited arc to vary continuously the effective area between them. In a design of this type it is important that the pivot point for each blade be located near the center of the blade so that the aerodynamic torque exerted on each blade by the fluid flowing across its surface to minimize the force required to control the assembly. However, when a blade is thus centrally pivoted without further provision, it is subject to the criticism that as it is rotated, the clearance between the edge of the vane and the adjacent rotor of the machine varies considerably. From an aerodynamic standpoint, both in compressor and turbine design, it is important that this clearance be kept as small as possible at all times. Accordingly, it is an object of the present invention to provide an adjustable blade which provides a reduced variation in clearance between an edge of the blade and an adjacent rotor.

It is another object of the invention to provide an improved adjustable blade assembly in which the individual blades are pivoted centrally to minimize aerodynamic torque thereon with means to maintain a small and constant clearance between an edge of the blade and an adjacent rotor.

Briefly, these and other objects of the invention are accomplished by providing means to change the radial position of the axis of rotation of an adjustable blade with respect to an adjacent rotor as the blade is rotated.

The invention will be better understood from the following description taken in connection with the accompanying drawing in which:

Fig. 1 is an elevation view showing an adjustable blade apparatus constructed in accordance with the invention;

Fig. 2 is an enlarged partial sectional view taken along the lines 2—2 of Fig. 1;

Fig. 3 is a partial elevation view of part of the structure shown in Fig. 1 showing the apparatus showing the blades in the closed position;

Fig. 4 is an enlarged sectional view taken along the lines 4—4 of Fig. 3;

Fig. 5 is an enlarged partial elevation view of the apparatus that is shown in Fig. 1 from the reverse side; and

Fig. 6 is a partial elevation view of the apparatus shown in Fig. 3 also from the reverse side.

2

Referring to Fig. 1, a radial flow type of rotor is indicated generally at 10. Mounted adjacent the rotor 10 is a plurality of circumferentially and uniformly spaced vanes 11. Each of the vanes is provided with a control shaft 12 of circular section which is mounted for rotation within an eccentric bearing 13. The bearing 13 is called "eccentric" in that it is cylindrical in cross section and the shaft 12 is journaled eccentrically therein. Each eccentric bearing 13 is in turn journaled in an opening 14' in a bearing support member 14 for rotation therebetween. Fastened to the end of each control shaft 12 to control the rotation thereof is a clevis member 15 which engages a pin 19 on a positioning ring 18. Clevis member 15 and pin 19 comprise linkage means for drivingly connecting positioning ring 18 with shaft 12 and vane 11 for rotation thereof. In order to rotate the eccentric bearing 13 within the support 14, a pinion 17 is fastened to the shaft which meshes with teeth on the periphery of the positioning ring 18. The pin and clevis can best be seen in Figs. 5 and 6. The pin and clevis arrangement then operates to rotate the control shaft 12 within the eccentric bearing 13 whereas the ring and pinion arrangement operates to rotate the eccentric bearing within its opening 14' in the bearing support 14 upon rotation of the positioning ring 18.

By proper sizing of the eccentric bearing 13 and the parts in the ring and pinion arrangement and also the clevis and pin arrangement described above, a resulting arrangement can be obtained in which the position of the vanes 11 is adjusted by rotating the positioning ring 18 to vary the flow area therebetween, but in varying from the closed position as indicated by Figs. 3, 4, and 6 to the maximum area position as shown in Figs. 1, 2, and 5, the clearance between the periphery 26 of the rotor 10 and the adjacent edge 27 of the blades 11 is maintained at a constant or nearly constant magnitude.

Thus, an improved adjustable vane assembly is provided in which the flow area between the vanes is variable, the minimum of aerodynamic torque exerted thereon and at the same time maintaining a desired clearance between the vanes and an adjacent rotor.

While a particular embodiment of the invention has been illustrated and described, it will be obvious to those skilled in the art that various changes and modifications may be made without departing from the invention and it is intended to cover in the appended claims all such changes and modifications that come within the true spirit and scope of the invention.

What I claim as new and desire to secure by Letters Patent of the United States is:

1. In a fluid flow machine the combination of a plurality of vanes circumferentially and equally spaced about a fluid flow rotor, each of said vanes being mounted for rotation about its own axis of rotation control means interconnecting said vanes to provide simultaneous rotation of each about its axis of rotation; and rotatable bearing means for each of said vanes, each of said bearing means being connected with said control means for simultaneous rotation about an axis offset from the axis of rotation of said vane journaled therein, to rotate said axis of rotation about said offset axis in a synchronized relationship such that an edge of said vane remains at a substantially constant distance from said rotor.

2. In a fluid flow machine having a rotor and a supporting structure, a plurality of rotatable bearing members journaled in said supporting structure and circumferentially spaced about an axis of rotation of said rotor, a plurality of vanes, a plurality of shafts each affixed to one of said vanes and eccentrically journaled in one of said bearing members, a clevis member affixed to each said shaft, a positioning ring circumferentially drivingly engaging said bearing members, and a pin driv-

ingly engaging each said clevis member and affixed circumferentially to said positioning ring, such that rotation of said positioning ring produces rotation of said vanes and said bearing members to adjust the positions of said shafts and said vanes in a predetermined synchronized relationship such that an edge of each of said vanes describes an arcuate circular path concentric with said axis of rotation of said rotor.

3. In a fluid flow machine including a rotor rotatable about a fixed axis, the combination of a plurality of vanes circumferentially spaced about said rotor, support means, a plurality of bearing means each rotatably supporting one of said vanes, each of said bearing means mounted in said support means for rotation about an axis offset from the axis of rotation of said one of said vanes supported therein, and control means drivingly connected with each of said bearing means and each of said vanes for simultaneous rotation thereof in a predetermined synchronized relationship such that a leading edge of each of said vanes describes a circular path concentric with said fixed axis.

4. In a fluid flow machine having a rotor, the combination of a plurality of vanes circumferentially spaced about an axis of rotation of said rotor, a plurality of shafts each connected to one of said vanes for rotation thereof, support means, a plurality of bearing means each rotatably supporting one of said shafts and a corresponding one of said vanes connected thereto, each of said bearing means mounted in said support means for rotation about an eccentric axis offset from the axis of rotation of the corresponding one of said shafts and a corresponding one of said vanes supported therein, and control means drivingly connected with said shafts and said bearing means to rotate each of said vanes and to rotate

4
said axes of rotation thereof about said eccentric axes in a predetermined synchronized relationship, whereby an edge of each of said vanes describes an arcuate circular path concentric with said axis of rotation of said rotor.

5. In a fluid flow machine including a rotor rotatable about a fixed axis, the combination of a plurality of vanes circumferentially spaced about said rotor, each said vane having a leading edge radially spaced a predetermined distance from said fixed axis, support means, a plurality of bearing means each rotatably supporting one of said vanes, each of said bearing means mounted in said support means for rotation about an axis offset from the axis of rotation of said one of said vanes supported therein, a plurality of linkage means each drivingly connected with one of said vanes, and rotatable positioning means drivingly connected with each of said linkage means and each of said bearing means for simultaneous rotation of each of said vanes and each of said bearing means, to rotate said axis of rotation of each of said vanes about said axis of rotation of each of said bearing means in a predetermined synchronized relationship such that the leading edge of each of said vanes remains radially spaced from said fixed axis substantially said predetermined distance.
